UNITED STATES PATENT OFFICE.

RALPH S. Langley, of Detroit, Michigan, assignor to the Straus Brothers Company, of Ligonier, Indiana, a corporation of Indiana.

DESIGN FOR A PAPER-WEIGHT OR SIMILAR ARTICLE.

53,203.

Specification for Design.

Patented Apr. 15, 1919.

Application filed February 10, 1919. Serial No. 276,080½. Term of patent 7 years.

To all whom it may concern:

Be it known that I, RALPH S. Langley, a citizen of the United States of America, residing at Detroit, in the county of Wayne and State of Michigan, have invented a new, original, and ornamental Design for a Paper-Weight or Similar Article, which is illustrated in the accompanying drawing, forming a part of this specification.

Figure 1 of the drawing is a front view, and

Fig. 2 is a rear view of the paper weight showing my new design.

What I claim is:

The ornamental design for a paper weight or similar article as shown.

RALPH S. Langley,

Witnesses:

Otis D. Nusbaum,
Catherine E. McLaughlin.
